UNITED STATES PATENT OFFICE.

OTHO B. KIRACOFF, OF CHURCHVILLE, VIRGINIA.

LIFTING JACK.

Application filed October 5, 1921. Serial No. 505,517.

To all whom it may concern:

Be it known that I, OTHO B. KIRACOFF, a citizen of the United States, residing at Churchville, in the county of Augusta and 5 State of Virginia, have invented certain new and useful Improvements in Lifting Jacks; and I do hereby declare the following to be a full, clear, and exact description of the invention, such as will enable others skilled 10 in the art to which it appertains to make and use the same.

This invention relates to a lifting jack.

An important object is to provide a construction of jack particularly useful in raising forms for concrete work so that such work may be accomplished more efficiently, with a considerable reduction in the time, labor and expense involved.

It is also aimed to provide a construction 20 of lifting jack which may be operated by fluid pressure and which is capable of operation in different adjusted positions as the work progresses, and which is of general construction hereinafter described in connection with accompanying drawings illustrating one practical embodiment thereof.

Additional objects and advantages will appear from said description.

In the drawings:—

- 30 Figure 1 is a side elevation;
 Figure 2 is an end elevation;
 Figure 3 is a vertical sectional view;
 Figure 4 is a plan view;
 Figure 5 is a cross section on the line 5—5
 35 of Figure 1;
 Figure 6 is a cross section on the line 6—6
 of Figure 1;
 Figure 7 is a cross section on the line 7—7
 of Figure 1, and
 40 Figure 8 is a detail view illustrating a modified form of the levers.

Referring specifically to the drawings, wherein like reference characters designate like or similar parts, 8 designates a vertical 45 rod, such as is usually employed in pluralities, to reinforce concrete work at its lower end, being first embedded therein or otherwise fastened thereto. Rod 8 therefor is to be considered as extending vertically from concrete work. An attaching or base plate 9 has an opening 10 therethrough, to receive rod 8 on which plate 9 may slide. Plate 9 is adapted to be fastened, in any suitable manner, as by means of screws, insertible 50 through openings 11, into the form or part to be raised or elevated. Surrounding a part of

the rod 8 and rigid with plate 9, is a yoke 12, between the arms of which a dog 13 is positioned, being pivoted upon a pin 14 removably secured in the arms of the yoke by 60 means of removable potter pins or the like 15. This lever 13 has a cam serrated face 14^a which fits into binding relation against the rod 8, by means of a suitable spring 16 having a portion 17 wrapped upon the lever, and a portion secured to the base as at 18. The shape of the face 14^a is such however that when the base plate 9 is elevated, the lever 13 will automatically yield to permit such movement but that when the plate reaches the 70 adjusted position and is released, the spring 16 maintains the face 14^a in binding engagement with the rods 8, so that descent or fastening of the base plate 9 along the rod 8 is 75 prohibited.

Rising from the fastening or base plate 9, at any suitable location, are a plurality of rods 19. These rods lead to a head plate 20. Both plates 9 and 20 preferably have openings therethrough to removably receive the 80 rods 19. Both ends of said rods 19 are provided with screw threads and nuts 21 work on the screw threads and engage opposite faces of the plate, to rigidly secure the rod and plates together. Plate 9 is preferably 85 reinforced at 22, where the rods 19 pass therethrough and preferably recessed as at 23, to receive the lowermost bolts 21, and to enable the lower surface of plate 9 to be plane, that is without projection, in order to more 90 intimately engage the form to which it is attached.

Plate 20 may be cut away as at 24 to accommodate the uppermost nuts 21 and such plate has a central opening 25, through 95 which rod 8 passes and on which it is slidably mounted. One or more cylinders 26, preferably in the form of tubes open at each end, may depend from the head plate 20. Any suitable means may be utilized in attaching cylinders 26 to plates 20 but as shown, the head plate 20 is provided with recesses 27, having their annular wall provided with screw threads, engaged by screw threads on cylinders 26 at 28. A manifold 100 passageway 29 is cut in the head 20 and opposite ends communicate with the recesses 27 and cylinders 26. Communicating with passageway 29 is an inlet port 30 and an exhaust port 31. Pipes or conduits 32 and 33, 105 respectively, communicates with ports 30 and 31. Pipe 30 has a cut off valve 34 there-

in, and pipe 31 has a cut off valve 35 there-shifting the valve 34 to closed position and in. An actuating rod member 36 is connected to valve 34.

Suitable pistons are slidable within the cylinders 26 and they preferably consist of heads 37 from which angularly disposed guide ribs 38 depend. Head 37 has a plurality of openings therethrough accommodating bolts 39 which pass removably through retaining discs 40 and leather or other washers 41, secured in place intermediate discs 40 and heads 37. Attaching plates may be provided preferably integral with the ribs 38 at each end as at 42 and 43 with bolts 39 passing removably through the former. Plates 43 may removably secure a piston base plate 44 in place, through the medium of bolts 45, which may pass through intermediate discs 46. A guide eyelet or the equivalent 47 is provided on base 44, through which the rods 36 is slidably mounted. The lower end of the rod may have an abutment 48 thereon, for instance as several nuts as shown.

Centrally of the plate 44, an opening 49 is provided through which rod 8 extends and on which the plate 44 is slidably mounted. Parallel upstanding bars 50 are formed, preferably integral with plate 44 and placed on opposite sides of the opening 49. On opposite sides of the rod 8, and intermediate bars 50, dogs 51 are disposed, being pivoted on removal pins 52 mounted by bars 50 and held in place as by means of cotter keys or the like 53. The inner ends of these bars are arcuate and serrated as at 54 so as to bind against rod 8 to prevent descent of the plate 44 and parts supported thereby, but to permit ascent of said plate and supported parts. A spring 55, surrounds levers 51 at 56 and at 57 such springs are secured to the plate 44. Levers 51 are similar to the lever 13 and if desired, serrations may be provided on a removable base plate 58 secured thereto as by means of a dovetailed rib and groove at 59 and a fastening end at 60. Springs 16 and 55 are similar.

With the rod 8 securely anchored and rising from a wall or cement work, for instance, and with the fastening plate 9 secured to the work, a supply of operating fluid, from any desired source, is admitted through port 30 with the valve 34 properly adjusted, through manipulation of the rod 36. The power medium thus enters manifold 29 and the cylinders 26, and through pressure, against the piston structures, causes the head 20 to rise and accordingly the fastening plate 9, together with the form attached thereto. When such form has been lifted or elevated to the desired extent, movement of the head 20 will have elevated the rod 36, bringing the abutment 48 into contact with the eyelet or abutment 47, thus

thus cutting off the supply of operating fluid and arresting lifting movement. Thereafter, when it is desired to elevate the form to a greater height, pressure in the cylinders 26 is released by operation of the valve 35. When thus relieved, plate 44 is elevated on the rod 8 with the dogs 51 yielding to facilitate the raising thereof and coacting with the rod 8 to prevent descent as described. Power fluid may then be again admitted through port 30 so that its action within the cylinders 26 will again raise the head 20, the plate 9 attached thereto and the form attached to fastening plate 9.

Changes within the spirit and scope may be resorted to.

I claim as my invention:—

1. A lifting jack having a lifting section provided with a base, a mounting member on which said base is slidable, a second base, said second base being slidable with said mounting member, means on said bases to permit sliding movement thereof in one direction and to resist sliding movement thereof in the opposite direction, a cooperating piston and cylinder supported, respectively, on said bases, and means operable to supply a power fluid to the cylinder.

2. A lifting jack consisting of a head, an attaching plate depending from the head, a supporting member relatively to which said head and attaching plate slide, means to secure the plate to the supporting member against movement longitudinally thereof in one direction, a supporting plate slidable on the supporting member, means to secure the supporting plate to the supporting member against movement longitudinally thereof in one direction, a piston on one of said plates, a cylinder on the other of said plates cooperating with the piston, and means for supply and exhaust of a power fluid to and from said cylinder.

3. A lifting jack, in combination with a supporting rod, a plate slidable on the rod, a dog on said plate for engagement with the rod to prevent descent of the plate, a head slidable on the rod, rods connecting said head and said plate, cylinders having an inlet and an exhaust passageway between said ports and said cylinder, a supporting plate slidable on the support, a dog pivoted to said supporting plate and engageable with the supporting member to prevent descent of the supporting member, pistons on the supporting plate entering said cylinders, a cut off valve, and means engageable by said plate to actuate said valve.

In testimony whereof I affix my signature in presence of two witnesses.

OTHA B. KIRACOFFE.
